UNITED STATES PATENT OFFICE.

LEON REES, OF LONDON, ENGLAND.

STUFFED DOLL, PUPPET, TOY FIGURE, AND THE LIKE.

1,139,997.

Specification of Letters Patent. Patented May 18, 1915.

Application filed October 17, 1914. Serial No. 867,137.

To all whom it may concern:

Be it known that I, LEON REES, a subject of the King of Great Britain, residing at London, England, have invented certain new and useful Improvements in Stuffed Dolls, Puppets, Toy Figures, and the like, of which the following is a specification.

This invention has for its object to construct stuffed dolls, puppets, toy figures and the like in such a manner that the head can be turned or placed in various positions and remain in the placed position.

My invention will be clearly understood from the following description aided by the annexed drawing which shows a front view partly in section of my invention applied to a doll.

In carrying out my invention I construct the head 1 and short neck separate from the body 2 and with a conical or other shaped tube 3 or equivalent projecting upward in the neck or lower part of the head 1 to approximately the center of said head. The end of the neck or lower part of the head 1 is rounded off with the open mouth of the tube 3 or equivalent in the center.

The body portion 2 of the doll is formed with a cup or semi-spherical recess 4 in the neck portion or between the shoulder and the edge of the cup may form the neck of the doll or the like.

The head 1 is connected to the body 2 of the doll by a piece of elastic cord 6, coiled spring or equivalent, one end 7 of which is connected to the top of the tube 3 in the head 1 or to a cross piece in the head 1 or in any other manner so that the elastic cord passes through the tube 3 or equivalent the other end 8 of the elastic cord being connected to about the middle of the cup 4 in the body.

The elastic thread is sufficiently taut to hold the head 1 tight to the body 2.

Copies of this patent may be obtained for five cents each, by addressing the "Commissioner of Patents, Washington, D. C."

The lower or neck portion of the head 1 is made large enough to rest in and practically fill the cup 4 or semi-sphere in the body 2 and to be capable of turning therein, and the tube 3 in the head will be of a diameter to allow the elastic cord to be always in a straight line and so insure the head remaining in any placed position.

What I do claim as my invention and desire to secure by Letters Patent is:—

1. A figure toy comprising a body provided with a cup-shaped member, a head provided upon said body and having its lower end resting in said cup-shaped member, a tubular member provided in said head and having its lower end opening out into said cup-shaped member, and elastic connecting means having one of its ends secured to said head at approximately the center of the same and having its other end secured to said cup-shaped member.

2. A figure toy comprising a body provided with a cup-shaped member, a head provided upon said body and having one of its ends so shaped as to snugly engage said cup-shaped member, a cone provided in said head and having its apex at approximately the center of said head, the large end of said cone opening out into said cup-shaped member, and elastic connecting means having one of its ends secured to the center of said cup-shaped member and extending through said cone and having its other end secured to the apex of said cone.

In testimony whereof I have hereunto set my hand in presence of two subscribing witnesses.

LEON REES.
